UNITED STATES PATENT OFFICE.

JEAN MARIE LAFFAS, OF LE VÉSINET, FRANCE, ASSIGNOR TO THE LAFFAS SYNDICATE, LIMITED, OF LONDON, ENGLAND.

APPARATUS FOR AUTOMATICALLY PREVENTING RAILWAY ACCIDENTS.

SPECIFICATION forming part of Letters Patent No. 659,307, dated October 9, 1900.

Application filed May 4, 1900. Serial No. 16,541. (No model.)

To all whom it may concern:-

Be it known that I, JEAN MARIE LAFFAS, civil engineer, a resident of the city of Le Vé-sinet, in the Republic of France, have invented new and useful Improvements in and Connected with Apparatus for Automatically Preventing Railway Accidents, which improvements are fully set forth in the following specification.

10 The present invention relates to improvements in apparatus designed to increase the safety in the running of trains or vehicles on railway-lines, more precisely to an automatic valve-motion actuating the brakes, to a stop-block placed at any point to be protected, and third, to counter rail-bars placed near any point of the line to be protected.

In order to render my invention more clear, I beg to refer to the accompanying drawings, 20 in which—

Figure 1 is an elevational view of the automatic valve-motion. Fig. 2 is a vertical section through the axis along the line 1 2 in Fig. 1. Fig. 3 illustrates a plan view of Fig. 25 2; Fig. 4, a section along the line 3 4 of Fig. 2. Fig. 5 shows an elevational view of the counter rail-bars. Fig. 6 is a plan view of said bars; Fig. 7, a side view of the same. Fig. 8 illustrates a side view of the wire support; Fig. 9, an elevational view of the stop-block; Fig. 10, a plan view, and Fig. 11 a side elevational view of the same.

The improved disengaging valve-motion comprises two casings *a b*, screwed together, 35 the casing *b* being furnished with two arms or branches *c d*, supporting a cross-pin *e*, on which a suspended disengaging lever *f* is loosely mounted. At the lower extremity of the lever *f* is a roller *g*, made of some supple 40 material and mounted to rotate about the axis *h*. The combined casings *a b* are supported by hangers *i j*, on the flat part of which they are bolted, the hangers *i j* being fixed at a suitable point to the locomotive or one of the 45 carriages.

In the interior upper part of the casing *a* is a valve *k*, the function of which is herein-after explained for working with compressed-air or vacuum brakes. An opening *l*, over 50 which the valve *k* is seated, is formed in the partition *m*, which separates the upper cham-

ber *n* from the lower chamber *n'*. This chamber *n* communicates with the opening of the pipe *o*, while the chamber *n'* communicates with the opening of the pipe *o'*, following 55 which is the train-pipe *c* in the case of a continuous air-brake.

In the lower casing *b* is the perforated or open chamber *p*, surrounded by a free space communicating with a pipe *q*, and in which 60 a piston *r* works. The bottom of the piston *r* rests on the flat part of the projection *s* of the depending lever *f*, while the bottom of the valve *k* rests on the head of the piston *r*. A screw-cap *t*, attached to the valve arrangement by a small chain when the brakes are 65 compressed-air brakes, enables the chamber *n'* to be closed against the external air, while the bottom of the valve *k* rests on the head of the piston *r*. The tightness of the joints is insured by means of membranes and india-rubber washers *u v x y*.

In the case of vacuum-brakes the construction of the valve arrangement or distributor is not in any way altered. The cap *t* is merely 75 removed, as also the membrane *u* beneath, which thus allows the external air to enter the chamber *n*, and the cap *t* is screwed onto the pipe *q* to close it. At the same time the apparatus is turned around in such a manner that the ejector is on the left following the pipe *o'* and at the end of the train-pipe *c*, 80 in which it produces a vacuum.

A sector *z*, with a raised rim and furnished at a suitable point with stop-teeth, is fixed to 85 the lower part of the casing *b*, while a spring-tongue piece *z'*, fixed on the depending lever *f*, rubs against the raised rim, coming into engagement with and resting on one of the stop-teeth when the disengaging lever is raised, 90 thus keeping the lever in the raised position.

In the case of continuous air-brakes the air comes from the head reservoir and through the pipe *o* into the chamber *n*, passes through the opening *l* in the seat, and fills the pipe *c*. 95 The brakes are thus released.

When the disengaging lever *f* is raised by the stop-block, which is arranged at a convenient point of the track in the path of the lever, the piston *r* descends and places the 100 chamber *n'* in communication with the pipe *q* and the external air. At the same time the

valve k also drops onto its seat l and prevents any compressed air from entering the chamber n' . The air contained in the pipe c' then escapes outside through the chamber n' , the open or perforated chamber p , and the pipe q and the brakes are promptly and firmly applied to the wheels.

If the brakes be arranged for working on the vacuum system, in which a steam-ejector constantly forms a vacuum in the train-pipe and keeps the brake-blocks away from the wheels, the cap t is removed from its seat and screwed onto the pipe q to close it, as hereinbefore described. This having been done and the lever f raised by the stop-block arranged on the track, the piston r descends into the chamber p and the valve k falls onto its seat l , thus preventing any communication between the chamber n' (which communicates with the suction-ejector situated at the end of the pipe, as well as the distributor) and the chamber n , into which and into the train-pipe which follows it the external air enters, the effect of this being to promptly and firmly apply the brakes. The automatic disengaging valve-motion or distributor can thus by simply removing the cap t be adapted either to compressed-air brakes of the Westinghouse or Wenger type, for example, or to continuous vacuum-brakes. In the first case it is also at the head of this pipe, but turned with the ejector at the left and at the end of the pipe o' .

The stop-block against which strikes the hanging lever of the before-explained distributor is represented in Figs. 9, 10, and 11. It consists of a strong but flexible plate c^2 , bent as illustrated in Fig. 9. To the axis a' of said block is fixed a lever b' , which is connected with signal-rod c' , actuating the signal. The axis a' is provided with an arm d' , carrying a counterweight p' , adapted to be regulated and designed to keep in equilibrium the flexible plate c^2 and its supports $a^2 b^2$. Thus the manipulation of the stop-block is rendered very easy as well as when effected by hand or by the weight of the wheels acting on the counter rail-bars, which will be hereinafter fully described. These bars are illustrated in Figs. 5, 6, 7, and 8. They are supported by the supports o^3 of the rails. In ordinary position these bars project somewhat above the rails, while the corresponding position of the stop-block is that in which the same is lowered and the line is free. When a train has passed over this stop-block and reaches that part of the rails which is provided with counter rail-bars, the latter will be depressed, and owing to the manipulating-wire and to the arm b^3 the stop-block is raised and the line is blocked. It thus will be clear that no train can enter the station or, more precisely, can reach that part of the rail provided with counter rail-bars until the stop-block is lowered again.

In order to facilitate the actuation of the counter rail-bars, they are equilibrated by means of the counterweight p^3 , fixed to the

prolongation d^3 of the lever b^3 , carrying the manipulating-wire e^3 .

Having now fully described and ascertained the nature of my invention, I declare that what I claim is—

1. The combination with the train-pipe of a fluid-pressure brake system, of a valve-chamber in the train-pipe said chamber being divided into two normally-communicating compartments with which the parts of the train-pipe respectively connect and through which they communicate, a normally-open valve for closing communication between the compartments of the valve-chamber, a second normally-closed valve for opening a passage from one of the compartments to the atmosphere, and means associated with the track for effecting the operation of said valves, whereby the brakes are applied.

2. The combination with the train-pipe of a fluid-pressure brake system, of a valve-chamber in the train-pipe said chamber being divided into two normally-communicating compartments with which the parts of the train-pipe respectively connect and through which they communicate, a valve normally opening communication between the compartments of the valve-chamber but closing a passage from one compartment to the atmosphere, and means associated with the track for effecting the operation of said valves as the train passes, whereby the brakes are applied.

3. The combination with the train-pipe of a fluid-pressure brake system, of a valve-chamber in the train-pipe said chamber being divided into two normally-communicating compartments with which the parts of the train-pipe respectively connect and through which they communicate, a valve normally opening communication between the compartments of the valve-chamber but closing a passage from one compartment to the atmosphere, a second normally-closed valve for opening a passage from the other compartment to the atmosphere, means independent of the valves for closing the passage from one compartment to the atmosphere, and means associated with the track for effecting the operation of the valves as the train passes, whereby the brakes are applied.

4. The combination with the train-pipe of a fluid-pressure brake system, a valve located in said train-pipe and adapted to open a port to the atmosphere to effect the application of the brakes, and a depending trip arm or lever for effecting the opening of said port, of a normally-lowered device associated with the track and adapted when raised to trip the depending arm or lever on the car as the latter passes, a normally-elevated counter-rail along the track connected with the tripping device and adapted upon being depressed by the car-wheel to elevate said tripping device into operative position to trip the arm or lever on the car and thus apply the brakes.

5. In an automatic distributor, the combi-

nation with a sector α furnished with stop-teeth and the spring-tongue pieces β rubbing against the raised rim of this sector, and engaging with and resting on one of these teeth 5 substantially and for the purposes as described.

In testimony whereof I have signed this

specification in the presence of the two subscribing witnesses.

JEAN MARIE LAFFAS.
